UNITED STATES PATENT OFFICE

2,368,815

AUTHENTICATING DEVICE FOR FILLED BOTTLES AND THE LIKE

Frederick W. Farrell, West Brookfield, Mass., assignor to Plymouth Cordage Company, Plymouth, Mass., a corporation of Massachusetts

Application September 23, 1941, Serial No. 412,040

3 Claims. (Cl. 40—134)

This invention relates to improvements in authenticating devices for filled bottles and the like.

More especially it relates to the authenticating of bottles in connection with their labeling, as regards their contents, and the identity of the maker or bottler thereof.

The labels of well-reputed makers of beverages, and of other liquids sold in bottles, are sometimes counterfeited, to aid the counterfeiter in dispensing other goods as being those having the high reputation, or for fraud in some other respect.

To detect such frauds, the stocks held by dealers for sale to the public have to be examined. It is difficult to determine whether a retailer's stock in trade is genuine, as labelled, or is spurious, because the visual aspect of goods and label can be copied very exactly by the counterfeiter. When a maker of the genuine employs inspectors for this purpose, he finds their work expensive, because the bottles have to be purchased and opened; and even then the available tests for comparing the counterfeit with the genuine product may be uncertain, because of the cleverness of imitation.

For best utility in distinguishing the genuine from the spurious, a test mark must be one that is not itself counterfeited; and to this end it is helpful if it can be perfectly invisible under ordinary conditions. A device useful in this situation has been disclosed in the patent granted to Dr. Ernest H. Huntress, No. 1,822,098, of September 8, 1931, by which an identifying mark, for authenticating the package, can be applied in such a way that the presence of that mark would not ordinarily be suspected, being ordinarily invisible, although it fluoresces to visibility under ultra violet rays.

In my co-pending application for patent Serial No. 277,599, filed June 6, 1939, leading to Patent 2,262,492, there is disclosed and claimed a label in which a fluorescent substance usable for this purpose, except that unfortunately it causes a slight but possibly discernible discolored, is embodied as an identifying and authenticating mark. By the invention there patented the discolored is obscured in ordinary light by being covered by part of the label, viz., surface material on either side of the label, but the substance fluoresces to visibility when ultra violet rays are applied to it through the thin surface gum or finish.

This present application is a continuation in part of my said co-pending application, and re-

lates to the authenticating of filled and sealed bottles and the like by means of a fluorescent marking substance located between the bottle and its label whereby in ordinary light it is effectively obscured. The obscuring elements are, on the one side, the whole label including its film of adhesive securing means; and on the other side the bottle, or the bottle-contents, or both. Yet it becomes visible under the effect of ultra violet rays applied through the label or through the bottle and its contents. This concealment and identification through the bottle can be had if the glass or other material of the bottle, or the contents of the bottle, or both bottle and contents, have sufficient obscuring character to hide whatever slight discoloration the test mark produces, as seen in ordinary light, and yet are combinedly sufficiently translucent to transmit ultra violet rays to the mark, and to pass the peculiar rays that emanate thence as an effect of the ultra violet rays.

The invention provides means by which such a mark, authenticating a labelled bottle, can be perfectly invisible to any ordinary handler of the bottle, and yet be so clearly readable by an inspector, equipped with apparatus for producing ultra violet rays, as to assure the inspector that the labelled bottle is genuine. If the maker has thus marked all of his output, of the kind in question, the finding on a dealer's shelf of a bottle which has all the ordinarily visible appearances of the genuine, but which is not bearing the authenticating mark, unequivocally detects that as a counterfeit.

In cases where either the bottle material or the contents, or their combination, is too opaque to pass the peculiar rays, a satisfactory result can be had by using material for the label which is sufficiently translucent. Ordinarily, paper can be successfully employed, but metal foil in the label will be a barrier to the desired rays.

In an embodiment of the invention, the fluorescent marking substance may be applied either directly on an exterior surface of a bottle and later be covered by the label; or may be applied on the back side of the label, which later is to be secured against the bottle. Either the bottle contents, or the material of the bottle, or the two combinedly, conceal the mark from observation on one side; and the body of the label conceals the mark from observation on the other side, but either the label or the bottle and contents are of a nature readily permeable by ultra violet rays and by the emanating fluorescence generated by

reaction of the ultra violet rays on the fluorescent substance between bottle and label. The natural opaqueness of a paper label, and the slight tint possessed by many beverages, or a tinted glass that may be selected for bottles of a colorless liquid, are sufficient to obscure the mark in ordinary light.

It is intended that the patent shall cover, by suitable expression in the appended claims, whatever features of patentable novelty exist in the invention disclosed.

In the accompanying drawing the single figure is a diagrammatic showing of a cross-section of a filled bottle, with label and authenticating test mark, in which the elements are diagrammatically separated from each other, and some are exaggerated in thickness.

Referring to the drawing, 10 represents an ordinary bottle or other container made of glass or a plastic composition or other transparent or translucent material.

The label 12 may be any ordinary label made of paper or other suitable material, carrying, in an ordinary way on its front face, printed or other information concerning the contents of the bottle and the maker or bottler of the contents.

The purpose of the invention is to provide a secret authenticating device to protect the trade and reputation of the party thus represented as maker or bottler, and also to provide an implement by which the public may be safeguarded against counterfeit products—assuming of course that the seal of the bottle or other container remains unbroken.

According to the invention, the fluorescent marking substance is 14, seen between the bottle 10 and its label 12 having its adhesive film 13 in the diagrammatic drawing. It may be applied to either the back of the label or the exterior of the bottle at a place where the label is to be later applied. In either case the putting of the label on the bottle covers the fluorescent mark from view in ordinary light, because it is enclosed between bottle and label.

The material of the bottle itself, and the contents, may be opaque, translucent or transparent. If either is opaque, the label must be of material penetrable by the invisible rays to which the mark responds, and by the visible rays with which it makes its response; yet sufficiently colored to obscure the mark. If the bottle and contents are translucent, the translucence in one or the other of these must be so limited that the two, or the one or the other, affords the obscurity sufficient to mask the fluorescent substance against visibility by one looking through the bottle and contents of the bottle. Most alcoholic liquors, for example, are of a nature to shield the mark adequately against visibility in ordinary light, yet are permeable by rays of ultra-violet light for generating from the fluorescent substance visible rays by which they also are permeable, so that the mark is thereby visible as an authenticating mark.

In the claims, the term "full bottle," when referring to its constituting the obscuring means, is intended to cover the situations where the obscuring is accomplished by either the bottle or its contents or these two together.

Material to constitute the fluorescent mark may be any of those substances in the nature of dyes mentioned in the said Huntress patent; or any other substance having the typical fluorescing characteristic and capable of being adsorbed or otherwise held on the bottle or the label, a considerable number of which substances are known.

Instances are found in the stilbene derivatives which are known to fluoresce, for example the free acid or a water-soluble salt of 4:4'-dibenzoylaminostilbene-2:2'-disulphonic acid or a substitution derivative thereof; also in anthracene, which may be dusted on, or applied in a suitable solvent.

For a safeguard against the fraud of soaking genuine labels off from their original bottles, and then applying them to bottles with spurious contents, a water-soluble fluorescent salt may be used. One such, which has the property of being invisible until ultra violet light is applied to it, is a sodium salt of 2-naphthol-3:6-disulphonic acid. Upon an attempt at removal of a label, so marked, the distinctive mark would be destroyed by the water applied for removing the paper from the bottle, or for washing the bottle with the label still on it.

On the other hand, by printing with petroleum jelly, carried in a suitable vehicle, for example, three times its volume of xylene, a mark is made which will not wash out in case the label of a bottle gets wet.

The concentration of percentage of the fluorescing material in the fluid for printing the authenticating mark may depend upon the fluorescent characteristics of the particular material selected for use, easily ascertainable by trial according to whatever strength may be desired. An illustrative formula for a vehicle, for applying the marking material in fluid form is, by weight:

	Per cent
Water	45
Glycerine (specific gravity 1.25)	55
	100

to which is added the desired proportion of fluorescent substance for which in many instances 2% will be found satisfactory.

The mark may be applied either by printing it, or marking it by hand as a signature or otherwise as may be convenient or preferred, on the bottle or on the gum on the back of a gummed label. In some cases the mark may be a mere covering of the whole back side of the label with a substance which fluoresces distinctively. Or, the mark may be a stippled or spotted aspect obtained by dusting a fine fluorescent substance, such as anthracene, on the back of the label, or on the bottle before the label is applied. Another method, which would offer marks in many distinctive combinations, is to mark the back of the label or the bottle by printing lines of different width and spacing, using fluorescent ink.

I claim as my invention:

1. A labelled package of merchandise, as, a sealed bottle or other container filled with a commodity, which labelled package is self-authenticating under ultra-violet rays; said package comprising the combination with the container of a labelling sheet secured exteriorly on the container, and a fluorescent marking substance, secured thereon by being enclosed between the container and said sheet, constituting an authenticating mark whose presence on the labelling sheet would be dimly visible if the mark were not covered, but whose character as a mark is invisible in ordinary light from either the front or rear of said package by these enclosing bodies; said fluorescent substance having the character that, when subjected to ultra violet rays, it fluoresces distinctively as an authenticating mark; the whole thickness of one of said obscuring bodies

being permeable by rays of ultra violet light and by the resulting visible fluorescent light which becomes generated by reaction of the ultra violet rays on the fluorescent substance, whereby said mark becomes visible through the obscuring means.

2. A self-authenticating package as in claim 1 wherein the fluorescent substance is applied on

the exterior surface of the bottle, and is covered by the label when the label is secured on the bottle overlying the fluorescent substance.

3. A self-authenticating package as in claim 1, wherein the fluorescent substance is applied on the back side of the label, and is covered by the bottle when the label is applied to the bottle.

FREDERICK W. FARRELL.
